ANSCO CORPORATION, OF BINGHAMTON, NEW YORK, A CORPORATION OF NEW YORK

FILM HOLDING BOX FOR CINEMATOGRAPH APPARATUS

Application filed January 28, 1929, Serial No. 335,642, and in Germany February 2, 1928.

The present invention relates to film holding boxes for cinematograph apparatus, more particularly to a very useful and practical shaping of the partition of such boxes.

5 In certain cinematograph apparatus film holding boxes are employed which have a partition forming a chamber for the receiving spool and another for the delivery spool. This partition serves also as a guide for the 10 film passing from the film feeding compartment to the film driving means and to the exposure position and from the latter to the receiving compartment; the guiding surfaces are covered with plush packing to ensure 15 that the chambers shall be light-tight. As it is impracticable to renew this packing on the fixed partition, the box becomes useless when the plush is too much worn to fulfill its purpose.

20 We found that this disadvantage is overcome by constructing box and partition in such a manner that the partition can easily be withdrawn, when the plush has been worn and a new one substituted for it. The blank 25 for the partition is stamped from sheet metal and then so bent that at one end of the partition two U-shaped guides are formed for the passage of the film, which at one end may be folded over in order to clamp the plush, 30 while at the other end the guide forming flanges form means for the light-tight connection with a side of the box, for example, they are bent over to lie parallel to the partition so as to form two slots in which corresponding inwardly projecting stepped flanges located on a wall of the box can engage, when the partition is inserted in the 35 box.

In the accompanying drawings an embodiment of the invention is shown.

Fig. 1 is an elevation of a stamped metal blank from which the partition is formed.

Fig. 2 is a side view of the partition made by folding the blank.

45 Fig. 3 is a view, drawn to an enlarged

scale, showing the engagement of the partition with the box.

Fig. 4 is a section on line 4—4 of Fig. 3.

Fig. 5 is a section through the charged film box.

50 Referring to Fig. 1, the stamped metal blank from which the partition is to be formed consists of a rectangular middle piece 1 bearing on the upper end of each lateral side a narrow strip 3 connected with 55 rectangular wings 4. To form the partition 2, the middle piece 1 is folded along the dotted line "a" in an angle of 180°, whereat the end of the partition 2 formed is splayed for a part of its length to form a slot 16. Then 60 the wings 4 are brought into position to form the U-shaped film guides 5 as seen in Fig. 4, by bending the strips 3 twice inward at right angles along the dotted lines b indicated in Fig. 1.

65 The ends 6 of the wings 4 are bent twice 70 rectangularly outward along the dotted lines d in order to form holders for the plush material 8. The ends 7 of the wings 4 are folded along the dotted lines c outward and bent in the form of stairs along the lines e to form guide slots 15 for receiving the stepped flanges 10 provided on the side wall 9 of the box as seen in Figs. 3 and 5. Notches 14 are provided as well in the middle piece 1 75 as in the wings 4 which after folding the partition in the manner described are adjacent to each other.

80 Into each film guide, thus formed by the wings 4, are inserted plush material 8 and 81 (see Fig. 5) between which the film 13 is to pass. The strips 8 are secured by passing one end of the strip around the end 6 of the wing 4. By the bending at 6 the plush is securely clamped. The strip 8₁ is held 85 in position with sufficient security by contact with the strip 8.

86 The partition 2 is inserted in the box when the cover is removed by engaging the ends 90 of the guideslots 15 of the partition 2 (formed

as hereinbefore described by a suitable bending of the ends 7 of the wings 4) with flanges 10 on the side of the box and sliding it along these flanges until it rests on the bottom 12 of the box; the other end of the partition 6 splayed for a part of its length at 16 slides on a pad 11 at the wall of the box.

For the exact positioning of the partition and further exclusion of light a ridge 17 is provided in the bottom 12 of the box, which ridge extends between the flanges 10 and engages the notches 14 in the partition 2 and the wings 4.

We claim:

15 1. In a film holding box for cinematograph apparatus a removable partition separating the film feeding and the film receiving compartments which partition has at one end two U-shaped guides for the film leaving and entering the box.

20 2. In a film holding box for cinematograph apparatus a removable partition separating the film feeding and the film receiving compartments which partition has at one end two U-shaped guides for the film leaving and entering the box, and means for light tight connection with the sides of the box.

25 3. In a film holding box for cinematograph apparatus a removable partition separating the film feeding and the film receiving compartments which partition has at one end two U-shaped guides for the film leaving and entering the box, and two slot forming flanges in which slots engage two flanges inwardly projecting from a side of the box.

30 4. A removable partition in accordance with claim 3 formed by folding a stamped blank of sheet metal.

40 5. A removable partition in accordance with claim 3 formed by folding a stamped blank of sheet metal, the film guides being covered with plush material.

45 6. In a film holding box for cinematograph apparatus a removable partition in accordance with claim 3 formed by folding a stamped blank of sheet metal.

50 7. In a film holding box for cinematograph apparatus a removable partition in accordance with claim 3 formed by folding a stamped blank of sheet metal, the film guides being covered with plush material.

55 8. In a film holding box for cinematograph apparatus a removable partition in accordance with claim 3 formed by folding a stamped blank of sheet metal, the film guides being covered with plush material, the other end of the partition being splayed, thus forming a groove, and a pad on the side wall of the box to engage with the said groove formed in the partition.

60 9. In a film holding box for cinematograph apparatus a removable partition in accordance with claim 3 formed by folding a stamped blank of sheet metal, the film guides being covered with plush material, the parti-

tion having a notch which engages a ridge provided in the bottom of the box and extending between the slot-forming flanges, the other end of the partition being splayed, thus forming a groove, and a pad on the side wall of the box to engage with the said groove formed in the partitions.

In testimony whereof, we affix our signatures.
